[57] CLAIM

The ornamental design for an interface unit for electronic bar code reader, as shown and described.

DESCRIPTION

FIG. 1 is a bottom, front, right side perspective view of an interface unit for electronic bar code reader showing our new design;

FIG. 2 is a top plan view thereof;

FIG. 3 is a left side elevational view thereof;

FIG. 4 is a rear elevational view thereof;

FIG. 5 is a front elevational view thereof;

FIG. 6 is a bottom plan view thereof.

The right side elevational view is identical to that shown in FIG. 3.

FIG. 1.

FIG. 2.

FIG. 3.

FIG. 4.

FIG. 5.

FIG. 6.
